(57) **CLAIM**

The ornamental design for a pet toy, as shown and described.

DESCRIPTION

FIG. 1 is a top perspective view of a pet toy in accordance with my new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof; and,

FIG. 8 is a back view thereof.

The broken lines shown in the drawings depict portions of the pet toy that form no part of the claimed design.

The term "JW" depicted in broken lines form no part of the claimed design. "JW" is a trademark owned by "DOSKOCIL MANUFACTURING COMPANY, INC."
